UNITED STATES PATENT OFFICE.

JOHN HENRY HOFFMAN, OF NEW YORK, N. Y., ASSIGNOR TO THEO. TIEDEMANN & SONS, INC., OF NEW YORK, N. Y., A CORPORATION OF NEW YORK.

MACHINE FOR MEASURING AND MARKING FABRICS.

1,287,314.

Specification of Letters Patent. Patented Dec. 10, 1918.

Application filed July 26, 1918. Serial No. 246,858.

To all whom it may concern:

Be it known that I, JOHN HENRY HOFFMAN, a citizen of the United States, and a resident of the city of New York, county of 5 Kings, and State of New York, have invented a certain new and useful Improvement in Machines for Measuring and Marking Fabrics, of which the following is a specification.

10 This invention relates to a machine for measuring and marking fabrics, such as piece goods, tapes, ribbons, or other like merchandise, and has for its object to provide an apparatus with which pieces of fabric or the like can be readily and expeditiously measured and marked in desired 15 lengths, thus obviating the necessity of laboriously measuring each piece of material into the lengths required for certain uses.

20 With this, and other objects which may hereinafter appear, in view, I have devised the particular arrangement of parts herein- 25 after set forth and more particularly pointed out in the claims appended hereto.

25 Reference is to be had to the accompanying drawings, forming a part hereof, in which,

Figure 1 is a plan view of a portion of a machine for measuring and marking fabrics 30 embodying my improvements;

Fig. 2 is a sectional view on the line 2—2 of Fig. 1, looking in the direction of the arrows;

Fig. 3 is a side elevation, partly in section, 35 of the mechanism for elevating the color applying roller and color trough;

Fig. 4 is a perspective view of a portion of one of the marking blades and the means for regulating the adjustment of the same; 40 and,

Fig. 5 is a plan view of a portion of one of the marking blades and the adjusting mechanism therefor.

Throughout the various views of the drawings, similar reference characters designate 45 similar parts.

In the preferred embodiment of my invention, as indicated in the accompanying drawings, 1 indicates the frame of the machine 50 which may be of any suitable outline or dimensions to meet requirements.

Journaled in suitable bearings in the frame is the main shaft 2. This shaft 2 carries a roller 3. On one end of the shaft 2 is fixed a pulley 4 which rotates the shaft 2 by 55 means of a belt 5 extending from a motor or other suitable driving mechanism.

Fixed on the shaft 2 is a sprocket 6 and this sprocket drives a marking roller 7 and an auxiliary winding roller 8 by means of a 60 chain 9 which passes over sprockets on the rollers 7 and 8. The auxiliary winding roller 8 is fixed on a shaft 10 extending transversely of the frame and this roller 8 is 65 adjacent the roller 3. Resting on top of the rollers 3 and 8 is an auxiliary roller 11, and the rollers 3, 8 and 11 allow the fabric to pass between them in the manner shown in Fig. 2 which will be hereinafter further 70 described.

The roller 11 can be lifted vertically when it is desired to pass the fabric between it and the rollers 3 and 8, as it is mounted at each 75 of its ends to rotate in a vertical member 12 of the frame, which is slotted as at 13 to receive the shaft 14 of the roller 11.

The marking roller 7 is mounted on the upper side of the frame 1 in suitable bearings 15. This roller 7 receives the marking preparation or color from a color distributing roller 16 which is mounted in bearings 17 in the color-holding trough 18. This trough 18 is provided at each end with a bracket 19 to which is pivotally fixed by the pin 20, a lever 21. These levers 21 are supported on a cross rod 22 which acts as a fulcrum for the same, whereby the roller 16, which receives the color 23 from the trough, is constantly kept in contact with the marking roller 7 by means of the weights 24, one 90 of which depends from the free end of each lever 21.

The rotatable marker 25 is mounted on top of the frame 1 at one of its ends. This marker 25 is mounted on a shaft 26 extending transversely of the machine and parallel to the various rollers heretofore referred to. The shaft 26 is mounted in suitable bearings 27 and these bearings are adjustable on the frame 1 by means of set screws 28 whereby 95 the marker may be brought nearer to or farther away from the marking roller 7 when 100

the device is adjusted to measure and mark various sizes.

Fixed on the shaft 26 are disks 28, and projecting radially from these disks are rods 29. Connecting these rods 29 are the marking blades 30. These blades 30 have serrated outer edges and are adjustably mounted on the rods 29 whereby they may be moved to and from the axis of the marker 5 when desired and thus the distance between each pair of marking blades may be varied to mark the fabric at desired distances. Each one of the blades 30 is provided with brackets 31 which embrace the ends 29 and 10 these brackets 31 are clamped to the rod 29 by means of set screws 32 whereby the blades may be securely held in any desired position.

From the foregoing the operation of my 20 improved measuring and marking device will be readily understood. The roll or piece of material to be measured and marked may be placed in any desired position on or adjacent the machine. The material 34 25 passes over a rod 33 extending transversely of the machine and thence passes about the marker 25, being supported on the blades 30 thereof, as shown in Fig. 2.

After passing over the marker 25, the 30 fabric 34 extends about a rod 36, and then around the rollers 8, 3 and 11, from which it extends to the final winding roller about which it is wound. The winding roller 37 is driven in any desired way so that it is 35 constantly winding or rolling up the marked fabric as the fabric passes through the machine, and has been marked by the marker.

It will be apparent that as the fabric passes through the machine, it acts as a belt 40 to rotate the marker and as each blade 30 contacts with the marking roller 7, the fabric which is interposed between the blade and the roller will receive a line of color extending transversely of the length of the 45 material. As the blades are situated the desired distance apart, and are adjustable or regulatable to desired distances, the marks on the fabric will thus be placed at equal and desired distances apart so that the material can be readily and expeditiously cut 50 to the desired lengths thereafter.

The arrangement by which the material is caused to move through the machine is, of course, not restricted to the exact manner 55 shown, as this may be successfully carried out in various ways, but the arrangement shown is a particularly expeditious and effective one, as the material is at all times held taut and without slack whereby very 60 accurate measuring and marking is assured.

From the foregoing, it will be obvious that my invention is not to be restricted to the exact embodiment shown, but is broad enough to cover all structures coming within 65 in the scope of the annexed claims.

Having described my invention, what I claim is:

1. A machine of the class described, comprising a rotatable marker having a plurality of radially extending rods, blades adjustable on said rods, a marking roller and means for causing said marker to rotate and carry material to be measured and cause a contact between each of the blades and the marking roller with the material interposed 75 between the blades and said roller.

2. A machine of the class described, comprising a frame, a rotatable marker mounted therein, bearings for said marker, a rotatable marking roller, means for moving 80 and adjusting the bearings of the marker to and from the marking roller, a plurality of blades on the marker adapted to support the material to be marked and means for adjusting said blades to and from the axis 85 of said marker.

3. A machine of the class described, comprising a frame, a shaft mounted therein, means for driving said shaft, a marking roller, means for driving the same, a rotatable marker, a plurality of radially extending rods on said marker, blades adjustably mounted on said rods upon which the material to be marked is supported and means for causing said blades to carry said material into contact at intervals with the marking 95 roller.

4. A machine of the class described, comprising a rotatable marker having a plurality of rods extending radially from its axis, 100 blades on said rods, said blades being adjustable to and from the axis of said marker, means for causing the marker to rotate and carry material to be measured on said blades, means for applying a marking line to said 105 material, said blades being adapted to cause a contact of the material with the mark applying means.

5. A machine of the class described, comprising a rotatable marker having a plurality of rods extending radially from its axis, 110 blades on said rods, said blades being adjustable to and from the axis of said marker, a trough for holding a marking preparation; a roller mounted therein, another roller for 115 receiving marking preparation from the first-mentioned roller, and means for causing said marker to rotate and carry material to be measured on the blades and cause a contact between each of the blades and the 120 last-mentioned roller, with the material interposed between the blades and said roller.

6. A machine of the class described, comprising a rotatable marker having a plurality of radially extending rods, blades extending longitudinally of said marker and adjustably mounted on said rods, a marking roller, means for driving said roller, a trough for holding a marking preparation, 125 a distributing roller rotatably mounted in 130

said trough and means for causing the distributing roller in the trough to be held in contact with said marking roller.

7. A machine of the class described, comprising a rotatable marker having a plurality of radially extending rods, blades mounted on said rods, a marking roller, means for driving said roller, a trough for

holding a marking preparation, a distributing roller in said trough, and a counterweight for holding said distributing roller in contact with said marking roller. ¹⁰

Signed at the city, county and State of New York, this 23rd day of July, 1918.

JOHN HENRY HOFFMAN.
